Meyers, Cavanaugh & Hyde

UNITED STATES PATENT OFFICE.

HARRY BRIDGMAN SMITH, OF BROOKLYN, NEW YORK, ASSIGNOR, BY MESNE ASSIGNMENTS, TO HOAGUE-SPRAGUE CORPORATION, OF LYNN, MASSACHUSETTS, A CORPORATION OF MASSACHUSETTS.

BOX STRUCTURE.

Application filed December 31, 1920, Serial No. 434,314. Renewed September 24, 1926.

My invention relates to covered boxes of paper or other materials which may be associated and formed in similar ways, characterized principally by the provision of the 5 central or body portion of the blank or box with wings and wing extensions composed of shell material and overlying cover material, and so constructed or arranged that in the completed box the inturned wing extensions 10 provide for concealing, by the overlying cover material, certain of the raw shell edges which would otherwise be exposed. Such exposed shell edges are unsightly and objectionable for many classes of boxes and the invention 15 provides for eliminating this objectionable feature in a simple and economical way.

The wing extensions also produce a very strong box structure and especially one which 20 is strongly reenforced at and near the wall corners.

The box is most conveniently produced from a box-blank assembly comprising a sheet of shell material and a sheet of cover 25 material adhesively secured together, with side-wing margins of the cover turned over upon and adhesively secured to upper margins of the shell side-wings, the assembly being formed with the side wings mentioned, 30 end (or corner) laps, end wings, and end wing laps, (all as explained in the following detail description), each of these assembly-blank members, in addition to the body-portion of the assembly, usually including portions 35 of both the shell and cover materials.

The principal objects of the invention are to provide a box adaptable to a great variety of uses for which covered boxes are required, and at the same time to provide a box structure 40 which is relatively inexpensive, both by reason of its structure and because it is adapted for economical methods of production.

The characteristics and advantages of the invention are further sufficiently explained 45 hereinafter, in connection with a detail description of the accompanying drawing, which shows certain exemplifying embodiments of the invention. After considering these, persons skilled in the art will understand 50 that many variations may be made within the principles of the invention; and I contemplate the employment of any structures which are properly within the scope of the appended claims.

Figure 1 is a perspective view of a box- 55 blank assembly.

Figure 2 shows the assembly side-wings folded up.

Figure 3 shows the end laps turned in.

Figure 4 shows the end wings bent up. 60

Figure 5 shows a completed box.

Figure 6 is a perspective view of one end of a modified blank-assembly.

Figure 7 is a detail, showing a step in the shaping of the modified assembly into box 65 form.

Figure 8 shows one corner of a box produced from the modified assembly.

The box-blank assembly shown in Figure 1 may be produced by a variety of preliminary 70 steps. It is composed of a sheet S of shell material, usually cardboard of suitable thickness, and an underlying sheet C of covering material, usually paper thinner than the shell material, and of suitable quality and finish 75 for boxes of the desired grade. These sheets are secured together, usually by adhesive applied between certain portions, or the entire areas, of their engaging faces. Preferably marginal portions 10 of the cover are turned 80 over and adhesively secured upon upper surfaces of the shell, thus providing in the present embodiment, a covering for the outward edges of the shell side wings.

The blank-assembly is shaped to provide a 85 body portion 11, side wings 12, end wings 13 with extensions 14, and end (or corner) laps 15, each of these blank portions comprising, most conveniently, portions of both the shell and the cover sheets. Desirably the upper 90 (inner) surface of the blank-assembly (consisting mainly of the upper surface of the shell) is creased or scored along the lines 16, to facilitate subsequent bending, and cuts 17 are made through both sheets to separate the 95 inner side edges of the end laps from adjacent portions of the end wings. The surfaces 18 of the end wing extensions are coated with adhesive, and adhesive is also applied to the outer surfaces 19 of the end laps, these 100 adhesive applications being made at any convenient time in the formation of the blank-assembly, or before or during the shaping of the assembly into box-form.

The side wings 12 are now bent up, as 105 shown in Figure 2; the end laps 15 are then turned in, as shown in Figure 3; the end wings are then turned up, and pressed against the

adhesive outer surfaces 19 of the end laps, as shown in Figure 4, and the upstanding end wing extensions 14 are then turned in and down, and their adhesive surfaces 18 pressed 5 against the inner surfaces of the end laps and intermediate inner surfaces of the end wings, producing a completed box (body or cover section, as the case may be) as shown in Figure 5, in which the cover material C over- 10 lies and conceals all exterior portions of the shell, except the edges of the shell end wings, which are more or less exposed, as indicated at e, Figure 5.

One end of a modified blank-assembly is 15 shown in Figure 6, in which the side-scorings 16 are extended along the lines 20, and cuts to separate the end laps are made along diagonal lines 22, producing end laps 21 having narrow outer ends, and end-wing-laps 23 20 connected with the ends of the end-wings 13 along the fold-lines 20. Adhesive is applied to the upper faces of the end-wing-laps, as shown. At a suitable stage of the shaping of the blank, conveniently after the end laps 25 21 are turned in, as shown in Figure 7, the end-wing-laps 23 are folded over along the fold lines 20, upon adjacent inner surfaces of the end wings, and their adhesive surfaces pressed in engagement with the end wings; 30 and when the end wings are subsequently turned up, the laps 23 are concealed under the end wings, as indicated in dotted lines in Figure 8; the end-wing extensions 14 are turned in and secured as in the structure first- 35 described. The edges of the shell material which are exposed at e, in the previously-described structure, are in the present case concealed by the infolded cover paper along the lines f, Figure 8; and no part of the 40 shell material is exteriorly exposed except very short portions g at the bent-over edges of the end wing extensions, adjacent to the side-edges; and these minute portions of the shell are practically unnoticeable, except 45 upon very careful inspection of the box.

Covered boxes constructed in accordance with my invention meet a very large demand for boxes of this class, and are more cheaply and rapidly produced than other styles of 50 covered-box construction.

The words "side" and "end" as here used, have a relative, rather than a limiting significance, since evidently if the length of the box sides is reduced, and the length of the 55 ends increased to a certain extent, the sides will appear to be ends, and vice-versa. Similarly, the end or corner laps might extend from the end wings instead of the side wings, and the extensions 14 or the laps 23 might 60 be connected with the side wings.

I claim:

1. A covered box, composed of a sheet of shell material and a sheet of cover material, and having a body portion, sides and ends, 65 the ends comprising inturned end laps, end

wings lying outside the end laps, end-wing extensions overlying the inner faces of the end laps, and end-wing laps connected to side-edges of the end wings and inturned between parts of the end wings and the adjacent end laps, thus providing that said side-edges of the shell end wings are concealed by overlying cover material.

2. A covered box, consisting of associated sheets of shell and cover material and including a body portion, side and end wings, end wing extensions, end laps and end wing laps, each of said component parts including portions of the shell and overlying cover materials, the end laps being secured between the end wings and the end wing extensions and the end wing laps being inturned between the end wings and adjacent surfaces of the end laps.

3. A box-blank assembly consisting of substantially coextensive blanks of shell and cover material adhesively connected, and comprising a body portion, side and end wings, end wing extensions, end-wing laps extending from side-edges of the end wings, and end laps extending from the side wings, said end wing laps being arranged, when the blank is folded to box form, to be inturned against inner faces of the end wings and thus to provide for covering and concealment of side-edges if the shell end wings by overlying cover material.

4. A covered box formed of two approximately similarly-shaped blanks, one of shell and the other of cover material, each blank having portions which jointly compose a box body, side wings, end wings, end-wing extensions, end-wing laps, and end laps extending from the side wings, the end laps being enclosed between the end wings and the inturned end-wing extensions, and the end-wing laps being inturned and secured between the end wings and the end laps, thus providing that said side-edges of the shell end wings are concealed by overlying cover material.

5. A covered box formed of two approximately similarly-shaped blanks, one of shell and the other of cover material, each blank having portions which jointly compose a box body, side wings, end wings, end-wing extensions, end-wing laps, and end laps extending from the side wings, the end laps being enclosed and adhesively secured between the end wings and the inturned end-wing extensions, and the end-wing laps being inturned and secured between the end wings and the end laps, thus providing that said side-edges of the shell end wings are concealed by overlying cover material.

Signed at New York city, in the county of New York and State of New York this 21st day of December, A. D. 1920.

HARRY BRIDGMAN SMITH.
